SOAP RECEPACLE

Joseph J. Settle, 1319 N. Fashion Lane 1,
Anaheim, Calif. 92806

Filed Nov. 27, 1970, Ser. No. 26,182

Term of patent 14 years

Int. Cl. D6—06

U.S. Cl. D33—24

FIG. 1.

FIG. 2.

FIG. 3.

FIG. 4.

FIG. 1 is a perspective view taken from the top, front and left side of a soap receptacle embodying my new design, the right side being the same as the side shown;

FIG. 2 is a sectional view taken generally along lines 2—2 of FIG. 1;

FIG. 3 is a rear elevation of the soap receptacle design; and

FIG. 4 is a perspective view of a modified form of the soap receptacle shown in FIG. 1.

I claim:

The ornamental design for a soap receptacle, substantially as shown and described.
